UNITED STATES PATENT OFFICE.

GUSTAVUS A. SCHLECHTER, OF READING, PENNSYLVANIA.

DESIGN FOR A BADGE.

SPECIFICATION forming part of Design No. 25,244, dated March 10, 1896.

Application filed June 10, 1895. Serial No. 552,354. Term of patent 3 $\frac{1}{2}$ years.

To all whom it may concern:

Be it known that I, GUSTAVUS A. SCHLECHTER, a citizen of the United States, residing at Reading, county of Berks, State of Pennsylvania, have invented a certain Design for Badges, of which the following is a specification.

The drawing represents my complete design, which comprises a main upper portion and a pendent portion linked thereto.

The leading features of the main upper portion of the badge consist in a keystone arch, within which is represented a coat of arms and the extremities of various tools and appliances apparently crossing each other in the rear and projecting beyond the outline of the arch.

The leading feature of the pendent portion of the badge is the novel representation of

fire-hose extending in wave-like form from a column at the top around a central circular field and terminating in crossed nozzles near the bottom, the contour lines being approximately circular, with a transverse suspension-bar at the top and the central field as well as the spaces between the folds of the hose suitably ornamented or inscribed.

What I claim is—

The design for a badge comprising main and pendent portions substantially as shown and described.

In testimony whereof I affix my signature in presence of two witnesses.

GUSTAVUS A. SCHLECHTER.

Witnesses:

W. G. STEWART,
ADAM L. OTTERBEIN.
